UNITED STATES PATENT OFFICE.

RENÉ GEELHAAR, OF NEW YORK, N. Y., AND PAUL SURY, OF JERSEY CITY,
NEW JERSEY.

ELECTRIC LAMP.

SPECIFICATION forming part of Letters Patent No. 250,438, dated December 6, 1881.

Application filed May 21, 1881. (No model.)

To all whom it may concern:

Be it known that we, RENÉ GEELHAAR, of the city, county, and State of New York, and PAUL SURY, of Jersey City, in the State of New Jersey, have invented certain new and useful Improvements in Electric Lamps; and we do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates to electric lamps; and it consists of a pair of hollow carbons, in combination with an inclosing-shell, electrical connections completing a circuit, and devices for holding said carbons in contact with one another.

It also consists in the combination of a closed shell or globe with a pair of carbons, a spring for pressing said carbons together, a metal sleeve provided with springs for holding one of the carbons, and electrical connections completing the circuit.

It also consists in certain other details of construction hereinafter set forth and claimed.

In the drawings, Figure 1 represents a central vertical section of our incandescent lamp. Fig. 2 represents a cross-section of the larger carbon cylinder. Fig. 3 represents a plan view of the clasp-springs holding the smaller carbon cylinder.

In Fig. 1 is shown a transparent shell or globe, A, provided with an annular rim, B, projecting from its exterior at the base. The said rim B rests on the plane of the annular projection C, which extends inwardly from the wall of the metal base D. The said wall is screw-threaded on its outer circumference, on which is screwed a metal collar, E, which is put into position by sliding it over the shell or globe A until it reaches the threads on the wall of the metal base D, and is screwed down until the annular projection F reaches the upper surface of the rim B, which is ground in order to insure a perfect air-tight joint.

The annular recess or channel G is provided with chemicals, which we employ for the absorption of oxygen which may exist within the

transparent shell or globe after having been hermetically sealed.

The central projection, H, of the metal base D is screw-threaded on the inner circumference of its wall, the said wall forming a chamber, 55 in which chemicals are placed, for the purpose as hereinafter stated. A copper pipe, I, is screwed into the projection H, and is screw-threaded on its inner surface at the top for the reception of a carbon cylinder, K, which is accurately adjusted by two or more springs, L L', 60 which are fastened to the copper pipe I by means of small screws. The upper portion of the carbon cylinder K is slightly inclined for the purpose of forming a perfect electrical contact with the smaller carbon cylinder M, which forms the incandescence of the lamp. The wall of this cylinder is made very thin in order to produce the desired effect. The said carbon cylinder M is held in position by four clasp-springs, N N' N² N³, a plan of which is shown in Fig. 3. The said clasp-springs are fastened to the base of a copper sleeve, O, held down in position by a steel spring, P, which rests on a projection of said sleeve O and presses 75 up against a copper collar, R, which is firmly fastened to the copper rod T, extending from the upper part of the interior of the shell or globe A, down through the carbon cylinders K and M, to a metal seat, W, into which it is 80 screwed, the said metal seat being insulated on the base of the chemical-chamber U, within the projection H, extending from the base D. The lower part of the metal seat W is made in contact with a metal strip, C, extending from 85 the same to the positive binding-post B, which is also insulated at the base D.

The electrical connection is made with the positive binding-post B, which conducts the current through the metal strip C, then to the 90 metal seat W, thence to the rod T, from said rod to the copper collar R, thence to the spring P, to the copper sleeve O, which is electrically connected with the clasp-springs N N' N² N³, holding the small carbon cylinder M, through 95 which the current travels to the larger carbon cylinder K, thence to the copper pipe I, which is electrically connected with the metal base D, which is also electrically connected with the negative binding-post d, thus completing 100

the electrical circuit required. The larger carbon cylinder K is made hollow, which is large enough to prevent an electrical connection with the copper rod T, which becomes heated by the 5 incandescence, thus causing the said rod to expand, and in doing so it forces the shell or globe A upward, by which a perfect air-tight joint is maintained in any degree of atmospheric temperature while the lamp is burning.

10 The entire lower edge of the smaller carbon cylinder M must touch the larger carbon cylinder K equally and slightly, as the electrical connection is made between them in the same manner as that of the Werdermann system.

15 In order to produce a vacuum or a partial or approximate vacuum within the shell or globe, it will be necessary to partly fill the annular chamber G with pyrogallate of potassium, sulphate of iron, chloride of iron, or metallic sodium, either of which is an absorbent of oxygen, whereby a partial vacuum or highly-rarefied condition of the contents of said shell will be produced and maintained by the absorption of the oxygen, leaving nitrogen gas of a low tension. 25 If the second chamber, U, be filled with freshly-burned charcoal, a large portion of the nitrogen will be absorbed and the approximation to a vacuum be made more nearly perfect.

Now, in order to protect the chemicals in the 30 chamber G from the heat of the incandescence, we employ two or more diaphragms, e e', of refractory substance, held against the copper pipe I, whereby we prevent all downward radiation of the heat, and at the same time keep 35 the joints comparatively cool. The said diaphragms will also arrest all small particles which may fall from the carbons and prevent them from coming in contact with the chemicals. The central chemical-chamber, U, is also 40 protected by a diaphragm, f, which operates substantially as that of the others, e e', and is held to the copper rod T. The perforated diaphragm g allows chemical action on the oxygen.

We are aware that it is old to employ within 45 an incandescent lamp a single hollow carbon of a cylindrical form which is electrically connected at each end by metal bands. This arrangement within a hermetically-sealed globe is objectionable, for the reason that the metal 50 bands attached to the carbons will become heated by the incandescence, causing the same to expand, whereby it will become disengaged, thus breaking the circuit and destroying the light at that portion, the consequence of which 55 produces an imperfect incandescence. This objection is obviated by a part of our invention, in which we employ two carbon cylinders to operate in the same manner as that of the Werdermann system, of which a full descrip- 60 tion has been given.

We are also aware that a diaphragm supporting metal rods for holding carbons within

a hermetically-sealed globe has also been employed; but in this case the rods are made in separate parts, one being much longer than that 65 of the other. When the two rods become heated they will expand; the longer one, expanding the most, will cause the carbons to separate beyond their electrical contact, thus breaking the electrical circuit, which at that moment destroys the light. This irregularity is objectionable, and is obviated by our invention, which we have so constructed that it is impossible to destroy the electrical connections 70 of the carbons by the expansion or contraction 75 of the metals.

Having fully described our invention, what we claim as new, and desire to secure by Letters Patent, is—

1. In an electrical lamp, a pair of hollow 80 carbons, in combination with an inclosing-shell, electrical connections completing a circuit, and devices for holding said carbons in contact with one another, substantially as described. 85

2. In an electric lamp, the combination of sleeve I, springs L L', attached thereto, and a carbon clasped by said springs and inserted in the end of said sleeve, with a second carbon, a spring which forces one of these carbons 90 against the other, and a closed shell or globe inclosing the aforesaid parts, substantially as and for the purposes set forth.

3. In an electric lamp, the combination of a closed shell or globe, a pair of hollow carbon 95 cylinders, spring P, copper sleeve O, carbon-holding springs N, and rod T, arranged and operating substantially as set forth.

4. In combination with a closed shell, A, and base D, having screw-threaded part H, the 100 upper pipe, I, engaging therewith, and diaphragms e e', supported by attachments of said pipe, substantially as set forth.

5. The base D of an electric lamp, formed with a receptacle, G, for oxygen-absorbing 105 chemicals, in combination with perforated diaphragm g, hollow shell A, and the carbons and electric connections, operating substantially as set forth.

6. The combination of tube I, externally 110 screw-threaded at one end, with base D, into which said end screws, springs L, which are attached to the other end, carbon K, clasped by said springs, carbon M, in contact with carbon K, and devices for holding said carbons 115 together and for completing the electric circuit.

In testimony that we claim the foregoing we have hereunto set our hands this 19th day of May, 1881.

RENÉ GEELHAAR.
